UNITED STATES PATENT OFFICE.

JOHN BIRNIE, JR., OF BIRNIE, MANITOBA, CANADA.

MAIL-BAG CATCHER.

1,113,301.

Specification of Letters Patent.

Patented Oct. 13, 1914.

Application filed October 17, 1913. Serial No. 795,720.

To all whom it may concern:

Be it known that I, JOHN BIRNIE, Jr., of the town of Birnie, Province of Manitoba, Canada, have invented certain new and useful Improvements in Mail-Bag Catchers, of which the following is a specification.

My invention relates to improvements in mail-bag catchers, and relates more particularly to that type of mail-bag catcher designed to be carried by a mail car and the function of which is to remove mail-bags from suitable supports positioned on a station, in such a manner as to deposit these mail-bags within the mail car, and the principal object of my invention is to construct a reversible mail-bag catcher which will normally extend in an angular position through the door way in the side of a mail car so that the contents of the mail-bags caught thereby will not be injured.

A still further object of my invention is to combine with my mail-bag catcher, an auxiliary net designed to catch a mail-bag in case my mail-bag catcher should not succeed in throwing the bag into the car.

Further objects of my invention will appear in the following specification.

Broadly considered, my invention comprises a member termed the mail-bag catcher, mounted to be slid in sockets carried by a frame movably mounted within the mail car, and means for supporting said mail-bag catcher in operative position, as hereinafter more particularly explained.

Figure 1 is a view of my mail-bag catcher as it appears from the inside of a mail car, certain parts being broken away and shown in section to illustrate certain details of construction. This view also shows a mail-bag carried by a suitable support, in position to be detached from the support by said mail-bag catcher, and thrown into the mail car.

Fig. 2 is a plan view of my mail-bag catcher showing the same in position ready to catch a mail-bag which is shown carried by suitable support. This view also shows a horizontal section through the side of the mail car on each side of the door or opening.

Fig. 3 is an elevation of one end of my mail-bag catcher, showing in side elevation, supporting means therefor which are positioned adjacent the vertical wall of the mail car, portion of which is illustrated in section.

Fig. 4 is a perspective view of the frame supporting the auxiliary net. Fig. 5 is a perspective view of the preferred form of

compound sockets used in mounting the mail-bag catcher, and Fig. 6 is a perspective view of the preferred form of locking means used to hold the mail-bag catcher in operative position.

In the drawings, like characters of reference indicate corresponding parts in each figure.

A is the side wall of the mail car and B the opening or door way therein. Mounted within the mail car in such a manner as to be readily swung into position at either side of the door way or opening B, is a suitable frame comprising a vertical member C with which is integrally formed an extension D at the upper end thereof, and at the lower end thereof an extension E. These extensions are each provided with bent ends d and e respectively which have bearing in the socket members F and G carried respectively by the wall A and floor H of the mail car.

Movably mounted on the member C are compound sockets I and J composed of vertical socket members K and horizontal socket members L, which are connected together. The vertical member C passes through the vertical socket members K, and in order to hold the said socket members in position from longitudinal movement on said member C, any suitable means may be used. I prefer to use ring-shaped collars M, one at each end of each vertical socket member K, and these collars are keyed in place by any suitable means such as pins or screws N secured in the vertical member C. The construction just described, or its equivalent, enables the compound sockets I and J to be readily moved on the vertical member C. Mounted to have longitudinal movement in the horizontal socket members L of the said compound sockets I and J, are the horizontal members O and P of the mail-bag catcher frame Q.

R is the lowermost horizontal member of the frame Q, and suitably connected therewith at each end are vertically disposed end members S and T, of the frame Q. The said end members S and T are also secured at their upper ends to the horizontal member O. Because of the construction already described, it will be understood that the frame O may be moved longitudinally in the socket members L, and the purpose of this movement will be hereinafter particularly set forth.

The function of the frame O is to come in

- contact with a mail-bag 2 carried by any suitable arm or support 3 and throw the bag into the mail car. Now in order to reduce to a minimum the impact against the mail-bags, the frame Q is provided with any suitable netting. A suitable type of netting is illustrated in the drawings, and the same 55 composes a plurality of light metallic rods 4, the ends of which are secured in suitable holes 5 formed in the end members S and T. Of course the netting will be carried by the frame Q so that this frame may be readily moved through the horizontal socket members L without interference.
- 10 15 In order to prevent the frame Q from being moved inwardly through the socket members L when the mail bag is struck, any suitable locking means may be provided. My preferred means comprises a collar 6 20 movably mounted on the vertical member C, and carried by this collar is a pierced lug 7 which carries the hook 8. In the position illustrated in Figs. 1, 2 and 3, my mail-bag catcher Q is in position to operate when the 25 train is moving in the direction indicated by arrow in Fig. 2. Now as the hook 8 is hooked through the eye 9 carried by the end member S, when the bag catcher strikes the mail-bag 2, it will not be slid within the 30 socket members L. In order to support the collar 6 in place, any suitable means may be provided such as collars 10 similar to those already described for supporting the compound sockets in place.
- 35 40 45 In order to brace the frame Q and prevent it from being moved around the vertical member C on the vertical socket members K, suitable bracing means must be provided. My preferred form of bracing means for this purpose comprises a rod 11, the bent end 12 of which rests in the socket member 13 carried by the jamb of the door or opening B. The outer end of the rod 11 is provided with an offset portion 14, preferably vertically disposed, and this off-set portion terminates 50 in a bent end 15. The bent end 15 is designed to be held in the pierced lug 16 carried by the horizontal member R, and the off-set portion 14 will rest against the inner 55 side of the pierced lug 16. A split pin or equivalent means 17 is held in a hole 18 formed near the outer end of the bent end 15 of the rod 11, to prevent the said end 15, and consequently the rod 11, from being accidentally withdrawn from the lugs 16.
- The construction just described supports the frame Q on the rod 11.
- Should the train be traveling in the direction opposite that illustrated in Fig. 2, 60 the mail clerk will unhook the hook 8 and remove the bent end 12 from the socket member 13, and by pulling on the rod 11, the frame Q will be drawn within the car. The clerk will then remove the rod 11 from the 65 pierced lug 16 and place it in the pierced

lug 16' carried by the member R. The frame Q will then be slid longitudinally through the socket members L and at the same time the vertical member C and its extensions will be moved into the dotted position shown in Fig. 2. The clerk will then place the bent end 12 of the rod 11 in the socket member 13' when the bag catcher will be supported in the dotted position shown. The hook 8 will then be hooked into the eye 75 9' carried by the member T.

In case the bag catcher should fail to throw the mail bag into the car, I prefer to provide an auxiliary net. In providing this auxiliary net 19, I utilize the rod 11, and 80 couple thereto an extension rod 20, the outer end 21 of which is bent and held in a hole 22 formed in the rod 11. 23 is a pin or other device held in the bent end 21 to keep this end in relationship with the rod 11. The 85 end 24 of the rod 20 is also bent, and in the position of the parts illustrated in Fig. 2, this bent end 24 is mounted in the socket member 13'. Should a bag drop before it is fully within the car, it will be understood 90 that the net 19 will catch the same. Not only does the extension rod 20 coöperate with the rod 11 in forming a frame for the support of the net 19, but it also performs the additional function of a thrust rod to 95 assist the rod 11 and hook 8 in bracing or supporting the frame Q. Without further description it will be understood that to reverse the position of the frame Q, the extension rod 20 can be readily removed and 100 placed. Both ends of the frame Q are identical so that the bag catcher may be readily reversed.

The end members S and T of the frame Q are preferably curved as illustrated, so that the lower horizontal member R will project beyond the other horizontal members to provide the frame Q with a ledge or lip which will facilitate the tossing of the mail-bag 110 into the car.

While I have described what I consider to be the best embodiment of my invention, I desire it to be understood that the principles can be embodied in different forms, and I desire not to be limited beyond the requirements of the prior art, and the terms of my 115 claims.

What I claim as my invention is:

1. A mail-bag catcher comprising a frame composed of a pair of horizontal members, one positioned above the other, and a pair of substantially vertically disposed end members connecting said horizontal members together; a movable frame comprising a vertically disposed member to each end of 120 which is connected a substantially horizontally disposed member the outer ends of which are adapted to have hinged connection; the said frame designed to be positioned between said horizontally disposed 125 members.

members of said movable frame and normally held at an angular position in respect thereto; means carried by the vertically disposed member of said movable frame in which the horizontal members of said frame have movement so that the position of said first mentioned frame and said movable frame may be reversed, and means whereby said first mentioned frame is locked and supported in operative position.

2. A mail-bag catcher comprising a suitable reversible frame designed to be supported at an angular position; a movable frame designed to be mounted within a mail car adjacent the door in the side thereof; a pair of compound sockets comprising vertical and horizontal socket members, mounted on said movable frame through the medium of said vertical socket members; means for holding said compound sockets from longitudinal movement on said movable frame; said first-mentioned frame being mounted to move within said horizontal socket members, and means whereby said first-mentioned frame is locked and supported in operative position.

3. A mail-bag catcher comprising a suitable frame designed to be supported at an angular position; a movable frame comprising a vertical member provided at each end with an extension; means whereby said extensions are pivoted in a mail car at the door in the side thereof; means carried by said vertical member in which said first-mentioned frame is mounted to have longitudinal movement so that the position of said first-mentioned frame and said movable frame may be reversed; means carried by said vertical member and engaging with said first-mentioned frame to lock said first-mentioned frame from longitudinal movement, and means for laterally bracing said first-mentioned frame.

4. A mail-bag catcher comprising a suitable frame designed to be supported at an angular position; a movable frame comprising a vertical member provided at each end with an extension; means whereby said extensions are pivoted in a mail car at the door in the side thereof; means carried by said vertical member in which said first-mentioned frame is mounted to have longitudinal movement so that the position of said first-mentioned frame and said movable frame may be reversed; means carried by said vertical member and engaging with said first-mentioned frame to lock said first-mentioned frame from longitudinal movement; means for laterally bracing said first-mentioned frame, comprising a rod removably connected with the outer end of said first-mentioned frame and designed to be removably supported at the door jamb of said mail car.

5. A mail-bag catcher comprising a suit-

able frame designed to be supported at an angular position; a movable frame comprising a vertical member provided at each end with an extension; means whereby said extensions are pivoted in the mail car at the door in the side thereof; means carried by said vertical member in which said first-mentioned frame is mounted to have longitudinal movement so that the position of said first-mentioned frame and said movable frame may be reversed; means carried by said vertical member and engaging with said first-mentioned frame to lock said first-mentioned frame from longitudinal movement; means for laterally bracing said first-mentioned frame, comprising a rod removably connected with the outer end of said first-mentioned frame and designed to be removably supported by the door jamb of said mail car; an extension rod pivoted in said first-mentioned rod near the outer end thereof, the inner end of said extension rod designed to be removably supported at the opposite jamb of said door, and a suitable net strung on said rods.

6. A mail-bag catcher comprising a frame composed of upper and lower horizontal members, an intermediate horizontal member, and vertically disposed end members to which said horizontal members are connected; a suitable netting carried by said frame; a movable supporting member for said frame; means whereby said supporting member is pivotally mounted; a pair of compound sockets each comprising vertical and horizontal socket members, the said vertical socket members being movably mounted on said supporting member; means for retaining said vertical socket members from longitudinal movement on said supporting member; the said upper and intermediate horizontal members of said frame being mounted in said horizontal socket members and having movement therein, and means whereby said frame is locked to said supporting member to prevent longitudinal movement of said frame in its socket members when the frame is supported in operative position.

7. A mail-bag catcher comprising a frame composed of upper and lower horizontal members; an intermediate horizontal member, and vertically disposed inwardly-curved end members to which said horizontal members are connected, the said lower horizontal member being positioned out of alignment with said other horizontal members to occupy an inward position in respect thereof; a suitable netting carried by said frame; a movable supporting member for said frame; means whereby said supporting member is pivotally mounted; a pair of compound sockets each comprising vertical and horizontal socket members, the said vertical socket members being movably

mounted on said supporting member; means for retaining said vertical socket members from longitudinal movement on said supporting member; the said upper and intermediate horizontal members of said frame being mounted in said horizontal socket members and having movement therein, and means whereby said frame is locked to said supporting member to prevent longitudinal

movement of said frame in its socket members when the frame is supported in operative position. 10

In testimony whereof I have affixed my signature.

JOHN BIRNIE, JR.
